[57] CLAIM

The ornamental design for a plant receptacle, as shown.

DESCRIPTION

FIG. 1 is a perspective view of a plant receptacle showing our new design;

FIG. 2 is a right side elevational view thereof with the left side elevational view being a mirror image thereof; FIG. 3 is a right end elevational view thereof with the left end elevational view being a mirror image thereof;

FIG. 4 is a top plan view thereof;

FIG. 5 is a bottom plan view thereof;

FIG. 6 is a sectional view thereof taken along the line 6—6 in FIG. 2;

FIG. 7 is a partial sectional view, on a larger scale, taken along the line 7—7 in FIG. 2; and,

FIG. 8 is a sectional view thereof taken along the line 8—8 in FIG. 5.

FIG. 1

FIG. 6

FIG. 7

FIG. 8
